UNITED STATES PATENT OFFICE.

CHARLES SCHENCK AND DWIGHT I. COOKE, OF CHICAGO, ILLINOIS, ASSIGNEES TO
FORSYTH BROS. COMPANY, OF CHICAGO, ILLINOIS, A CORPORATION OF ILLINOIS.

STATION-INDICATING DEVICE.

1,032,160.

Specification of Letters Patent. Patented July 9, 1912.

Application filed August 3, 1911. Serial No. 642,114.

To all whom it may concern:

Be it known that we, CHARLES SCHENCK and DWIGHT I. COOKE, both citizens of the United States, and both residing at Chicago, in the county of Cook and State of Illinois, have invented certain new and useful Improvements in Station-Indicating Devices, of which the following is a specification.

10 This invention relates to a device adapted to be installed upon public conveyances, for the purpose of indicating to the passengers the stopping point which the conveyance is approaching.

15 The objects of the present invention are, to construct a mechanism which will be compact in form, cheap and simple of construction and operation, and which will project the characters in a manner so that they 20 will be clearly legible under various light conditions, and in which a relatively small character-bearing ribbon can be utilized; and to so arrange the mechanism for projecting the characters that, when projected, 25 the characters will be of a size to be clearly legible from any point in the conveyance.

A further object of the invention is to 30 construct a cheap and simple mechanism for advancing the character-bearing surface in a step by step manner, and to so arrange 35 this mechanism that it can be automatically or manually operated; and to provide a simple and effective means for reversing the direction of movement of the character-bearing surface, which reversal can be effected without any shifting or re-arrangement of the mechanism.

Further objects will appear from a detailed description of the invention, which 40 consists in the features of construction and combination of parts hereinafter described and claimed.

A preferred construction is illustrated in the drawings, in which—

45 Figure 1 is a diagrammatic view, showing the front of a passenger car, with the indicating mechanism of the present invention in operative position thereon; Fig. 2, a transverse section through the car body, 50 showing the projecting surface; Fig. 3, a perspective of the indicating mechanism, showing the housing partially broken away; Fig. 4, a front view of the mechanism; Fig. 5, a plan view; Fig. 6, a detail of the mechanism for advancing the character-bearing

surface, said mechanism being in normal or non-operative position; Fig. 7, a view similar to Fig. 6, showing the mechanism in operative position; Fig. 8, a vertical section, showing the light and lens for projecting 60 the characters; Fig. 9, a detail, showing a modified structure for operating the mechanism to advance the character-bearing surface; and Fig. 10, a detail showing a second modified structure for advancing the 65 character-bearing surface.

As illustrated in the drawings, the device is shown embodied and used in connection with an ordinary street car, but it is, of course, understood that this is merely for 70 illustrative purposes to show one method of applying the device, and that the invention is intended to be applied to any public conveyance where such a device would be of any essential benefit.

75 The device comprises a casing 11 which, as shown in the drawings, is positioned upon the roof 12 of the car body 13. Attached to the forward end of the casing is a framework 14, which carries a projecting 80 surface 15 which may be of ground glass or other suitable substance; and the projecting surface, as shown more clearly in Fig. 2, is positioned at one end of the car body and elevated to sufficient height to be clearly 85 discernible to the passenger.

Carried by the casing 11 is a forward partition 16 and a rear partition 17. The forward partition 16 serves as a mounting for the framework 14 carrying the projecting surface, and also serves as a mounting for a projecting lens 18. The rear partition 17 serves as a mounting for a condensing lens 19, and said rear partition is also provided with a slot or opening 20 of a size 95 to accommodate a set of characters upon the character-bearing surface.

Positioned to the rear of the condensing lens 19 is a luminous center 21, which, in the form shown, consists of the ordinary incandescent light, which may be operatively connected to the lighting circuit of the conveyance or to an independent battery. Intermediate the partitions 16 and 17 is positioned an upper feed roll 22 and a lower 100 feed roll 23, which rolls receive and serve as a mounting for a character-bearing surface 24, preferably of transparent, flexible material, having suitable characters 25 positioned thereon. The characters may be of 105 110

a small design, and the character-bearing surfaces, necessary to accommodate all of the characters essential in ordinary use, will be of a size to be accommodated in a relatively small space. This is an important point in devices of this nature, as heretofore, in all prior constructions of which we are aware, it has been necessary, in order to have a character which would be large enough to be legible to the passengers in the car, and, in order to provide enough of these surfaces to accommodate the necessary characters, to form the character-bearing surface of an elongated strip which requires a large space to operate in and hence is difficult of installation, or else to provide a character-bearing surface which is of a large, bulky nature and hence requires a complicated and expensive mechanism to operate the same. In the present construction, through the use of a light and a suitable arrangement of lenses, it is possible to secure a projection, from a series of characters of small design, which will be large and easily legible from a distance. By using the condensing lens 19, we are enabled to concentrate the full force of the light from the lamp upon the opening 20, so that the full efficiency of the light is obtained during the operation, and through the use of the projecting lens 18 the light is refracted, after passing through the opening 20, so that the characters, when thrown upon the projecting surface, will be large enough to be clearly legible; and by concentrating the full force of the light upon the character-bearing surface a sufficient degree of light is obtained, so that the light surrounding the characters upon the projecting surface will be strong enough to render the characters legible during the daylight or under the influence of the strong artificial light employed in public conveyances at night. Hence, the characters will be clearly legible under all conditions of varying light which are met with in traveling conveyances. This is also deemed an essential and important point in the present invention.

50 The use of the transparent flexible strip in combination with opaque letters mounted on the same is important, because this arrangement allows of preparing different sets of strips lettered according to the different runs or car schedules. In the event of a car being taken from one run and placed on another, the only change of the apparatus required is a replacement of the character-bearing surface. By the use of this character-bearing surface, it is possible to indicate within a compact space, a great number of stations or stops on a comparatively short strip of material. In ordinary practice, best results have been obtained in the use of a strip two inches wide, with

letters three-sixteenths of an inch high, and with names spaced one-fourth of an inch centers. This allows of a compact arrangement of mechanisms for operating the flexible strip in either direction. It is obvious that any suitable flexible character-bearing surface may be employed, provided the same is transparent or translucent, and the characters mounted thereon are opaque. In order to prevent too great a loss in intensity of rays of light projected through the strip, it is essential that the strip be as nearly transparent as possible. It is realized that an image might be projected on the screen with this apparatus, using an opaque flexible strip, with transparent characters, on the same, but it is not advisable, on account of reducing the volume of the light projected through the film.

55 In projecting a sharply defined image on a screen, so as to be visible in the car interior, it must be borne in mind that where the character consists of a group of opaque letters three-sixteenths of an inch high, it is essential to employ such combination of lenses as will magnify the characters so that the resultant image on the screen will be of such size that it may be easily read from all parts of the car. Moreover, in order that the image on the screen may be clearly discernible in daylight, or when the car is operated with artificial light, it is also essential that the intensity of the light projected through the lenses be greater than the light at the point where the image is displayed.

60 In other words, to produce the desired contrast of light and shadow necessary to show a clear and sharply defined image on the screen, the luminous center must be of relatively high intensity or candle-power; and this is also necessary to compensate for loss in intensity of light, which occurs when the character is projected through lenses having high magnifying power. In ordinary practice, it has been found that the best results are obtained by the use of a simple lens, having a magnifying power of eight or ten to one, with a focal length of approximately twelve inches to fourteen inches, and, in order to obtain the best results as regards the focus of the rays of light from the luminous center on the character-bearing strip, the condenser is employed, consisting of a simple lens so designed as to condense the rays of light.

65 The roll 22 has secured thereto and may be operated by a shaft 26, and the roll 23 is mounted upon and may be actuated by a shaft 27. Each of the shafts 26 and 27 may be operated by mechanism of similar construction, save that the operating parts are so arranged and positioned with respect to one another that a reverse direction of movement is imparted to the roll 23 from that imparted to the roll 22. This, however, will

be dealt with more in detail farther on in the specification; but, inasmuch as the two mechanisms may be exactly similar in construction and operation, it is not deemed necessary at this time to enter into a detailed description of more than one of the mechanisms, save to describe the changes in the positioning of the parts necessary to effect the reversal of movement of the rolls.

10 In the form shown in Fig. 3, the mechanism is operated through the influence of a solenoid 28 of any usual and well known construction, which is energized from any suitable source of electrical supply, as, for instance, through the connection with the controller box shown in Fig. 1 and said solenoid. The energizing of the solenoid imparts movement to a stem 29 extending out therefrom, and said stem has secured to its outer end link members 30, and loosely mounted upon the shaft 27 are arms 32. Pivotally mounted upon a pin 32^a passing through the arms 32 is a dog 33, the upper end of which is connected to the links 30; and said dog operates upon a ratchet wheel 34, which wheel is fixedly secured to the shaft 27; and attached to the dog 33 at a point below the pivotal center thereof is a tension member 35, and the movement of the dog is limited in one direction through the medium of a suitable stop member 36. The stem is returned to its normal position after the solenoid has been energized by means of a spring 36^a located within the interior of the solenoid, as shown more clearly in Figs. 6 and 7, and said spring is interposed between the wall of a recess in the end of the stem and a cap 36^b in the end of the solenoid; and this spring further serves to exert a pressure on the dog 33, to force it into raised position. The principle of operation of the dog for actuating the ratchet is as follows: When the stem 29 is moved forward through the energizing of the solenoid 28, the arms 32 and the links 30 will be moved in a corresponding direction through the medium of the connection therebetween, and said movement will tend to swing the pivot of the dog in a counterclockwise direction, parallel to the periphery of the ratchet wheel 34. The links 30 are pivotally connected to the stem 29 and to the dog 33. The dog 33, however, is connected to the arms 32, and said dog is loosely mounted upon the pin 32^a which passes through the arms 32; hence, when movement is imparted to the stem 29 and the dog 33 is moved with the arms 32 which swing from the pivotal center of the shaft 27, and since the ratchet wheel 34 is carried by said shaft, it follows that the swinging movement imparted to the pivot of the dog 33 through the actuation of the stem 29 will be one parallel to the periphery of the ratchet wheel 34. While the arm 32 is being moved in this direction, the tension member 35 will be exerting a constant retarding movement thereon, and the acting end of the dog will be forced downward by the movements of the stem 29 and brought into acting engagement with the teeth of the ratchet wheel 34. Hence, a downward and forward movement will be simultaneously imparted to the dog, which is the movement necessary in order to bring the dog into proper engagement with the teeth of the ratchet wheel 34 to actuate the same. The solenoids are energized from any suitable source of electrical supply, as, for instance, through the connection with the controller box shown in Fig. 1, and said solenoids are connected in any suitable manner with a switch mechanism 37, which may be positioned upon the vestibules of the car and actuated by the motorman or conductor, or in any other suitable manner, although it is understood, of course, that this mechanism can be operated by means of a fixed contact of any suitable nature, without departing from the spirit of the invention. By employing a fixed contact, the operation of the feed rolls would become automatic in place of partially manual. As shown more clearly in Fig. 4, the mechanism for operating the feed roll 22 has its parts so arranged that, when actuated, a reverse movement will be imparted to said roll from that imparted to the feed roll 23. A solenoid 38 is positioned below a ratchet wheel 39 in place of above the ratchet wheel, as is the case in the mechanism for actuating the feed roll 23, and hence a dog 40 will be operating upon the lower edge of said ratchet wheel in place of the upper edge, as is the case with the dog 33. This, of course, will result in a reverse movement being imparted to the ratchet wheel 39 through the actuation of the dog 40 than that imparted to the ratchet wheel 34 through the actuation of the dog 33. Hence, when the switch connection is thrown so as to energize the solenoid 38, the direction of movement of the character-bearing surface will be the reverse from that imparted to it when the switch is thrown to energize the solenoid 28, so that, when the end of the line is reached, the character-bearing surface can be operated in a reverse direction, and the characters thereon displayed in their reverse order during the return trip, or, if through inadvertence the operator should fail to actuate the character-bearing surface at the point desired, he could move the surface twice before the next point was reached, and hence have the station displayed correspond at all times with the station which the conveyance is approaching. By this arrangement of the dogs and ratchets, one dog is slipping over the teeth of its ratchet wheel while the other dog is in operative position upon the teeth of its ratchet; hence no retarding movement is produced by having

one dog act against the other during the actuation of the feed rolls.

The operation will be understood from the foregoing, but briefly is as follows: For purposes of illustration, we will say that the operator pushes the button of the switch device marked Down. This will energize the solenoid 28, drawing the stem 29 thereinto, and through the medium of the link connection 5 swing the dog 33 forward. At the same time that this forward movement is imparted to the dog, the spring 35 will exert a pressure on said dog below its pivotal center, tending to throw the acting end of the 10 dog downward into engagement with the teeth of the ratchet, and the movement of the stem 29 will, accordingly, advance the dog 33 when it is in operative engagement with said teeth, and hence the shaft 27 will 15 be rotated through the movements of the ratchet wheel 34, and the character bearing surface 24 moved a sufficient distance to remove one set of characters from in front of the opening 20 and position another set 20 therein. When a reverse movement of the character-bearing surface is desired, the button of the switch member marked Up will be pushed by the operator, and the solenoid 38 energized to actuate the dog 40 to impart 25 movement to the feed roll 22, which movement will be the reverse of that imparted to the roll 23 through the actuation of the dog 33.

In Fig. 9 is shown a modified form of 30 structure for actuating the dog mechanism by means of a medium under pressure, as, for instance, compressed air. In this instance, a piston 41 is used, to which the stem 29 is connected, and said piston travels with 35 in a cylinder 42, and the medium is controlled by means of suitable valve mechanism 43 to cause it to enter either cylinder of the set of cylinders desired to actuate the feed roll 22 or the feed roll 23, and so impart 40 movement in the desired direction to the character-bearing surface.

In Fig. 10 is shown a second modification, in which the operation of the mechanism for actuating the feed rolls is entirely manual. 45 In this structure, a cable 44 is utilized, which is attached at one end to the link mechanism carrying the dog, and to the other end is attached a suitable grip 45, and a cable passes over suitable guide pulleys 46. 50 In the modification of Figs. 9 and 10, however, the same principle of construction is employed as that set forth in describing the operation of the device by means of the solenoids.

60 The extreme compactness of the device is such that it may be built into the upper portion of the car and at either or both ends thereof, as desired, and to be snugly positioned adjacent and transversely of the deck sash windows, which, obviously, is essential

in practical car construction. Furthermore, it will be noted that the operating conditions and requirements of this indicating device are radically different from that encountered in houses and theaters, since extreme compactness is essential and since the light conditions in such places are of a nature to admit of a ready discernibility of the projected characters without overcoming a conflicting light, which would ordinarily render the same indiscernible. 75

Without specifically limiting ourselves to the aforesaid constructions, we claim:

1. In a station indicating device, the combination of a car, a flexible transparent 80 character-bearing surface, opaque characters upon the surface, a projecting surface visible from the interior of the car, a luminous center, said luminous center being of greater luminous power than the ordinary light conditions of a car interior for displaying the characters, and means for moving the character-bearing surface, substantially as described.

2. In a station indicating device, the combination of a car, a flexible translucent character-bearing surface, opaque characters upon the surface, a projecting surface visible from the interior of the car, and a luminous center, said luminous center being 95 of greater luminous power than the ordinary light conditions of a car interior for displaying the characters, and means for moving the character bearing surface, substantially as described. 100

3. In an indicating device, the combination of a car, a character-bearing surface composed entirely of a flexible material, characters formed on said surface, the character-bearing surface and characters being 105 of different degrees of transparency, a projecting surface visible from the interior of the car, a luminous center, said luminous center being of greater power than the ordinary light conditions of a car interior for displaying the characters, a series of lenses arranged operatively with respect to the character-bearing surface and the luminous center, whereby a relatively large reproduction of the characters is thrown upon the 110 projecting surface, and means operatively connected for advancing the character-bearing surface in a step by step movement, substantially as described.

4. In an indicating device, the combination of a car, an elongated translucent and flexible character-bearing surface, opaque characters upon said surface, a projecting surface visible from the interior of the car, a luminous center, said luminous center being 115 of greater power than the ordinary light conditions of a car interior for displaying the characters, a series of lenses arranged operatively with respect to the character-bearing surface and the luminous cen- 120

130

ter, whereby a relatively large reproduction of the characters is thrown upon the screen, and means operatively connected for advancing the character-bearing surface in a step by step movement, substantially as described.

5. In an indicating device, the combination of a car, a character-bearing surface having characters formed thereon and composed entirely of flexible material, the characters and bearing surface being of different degrees of transparency, a projecting surface visible from the interior of the car, a luminous center, said luminous center being of greater power than the ordinary light conditions of a car interior for displaying the characters, a condensing lens interposed between the luminous center and the character-bearing surface, an enlarging lens interposed between the character-bearing surface and the projecting surface, whereby a relatively large reproduction of the characters is thrown upon the projecting surface, and means operatively connected for advancing the character-bearing surfaces in a step by step movement, substantially as described.

6. In an indicating device, the combination of a flexible character-bearing surface having characters formed thereon, the characters and bearing surface being of different degrees of transparency, a projecting surface, a luminous center, said luminous center being of greater power than the ordinary light conditions of a car interior for displaying the characters, condensing lenses interposed between the luminous center and the character-bearing surface, an enlarging lens interposed between the character-bearing surface and the projecting surface, whereby a relatively large reproduction of the characters is thrown upon the projecting surface, companion feed rolls for the character-bearing surface, means operatively connected for actuating the feed rolls, and means for reversing the direction of rotation of the feed rolls, substantially as described.

7. In an indicating device, the combination of a car, a casing, a character-bearing surface within the casing composed entirely of flexible material, and having characters formed thereon, the characters and bearing surface therefor being of different degrees of transparency, a luminous center within the casing, said luminous center being of greater power than the ordinary light conditions of a car interior for displaying the characters, a partition wall between the character-bearing surface and the luminous center, said partition having an opening therein of a size to accommodate the characters, condensing lenses interposed between the luminous center and the partition wall and in alinement with the opening therein,

a projecting surface visible from the interior of the car, an enlarging lens interposed between the projecting surface and the character-bearing surface, and means for actuating the character-bearing surface in a step by step movement, substantially as described.

8. In an indicating device, the combination of a character-bearing surface composed entirely of flexible material, characters formed on said surface, the character-bearing surface and the characters being of different degrees of transparency, a projecting surface, a luminous center, said luminous center being of greater power than the ordinary light conditions of a car interior for displaying the characters, a series of lenses arranged operatively with respect to the character bearing surface and the luminous center, whereby a relatively large reproduction of the characters is thrown upon the projecting surface, means operatively connected for advancing the character-bearing surface in a step by step movement, and means for reversing the direction of movement of the character-bearing surface, substantially as described.

9. In an indicating device, the combination of a casing, a character-bearing surface within the casing, composed entirely of flexible material and having characters formed thereon, the characters and bearing surface therefor being of different degrees of transparency, a luminous center within the casing, said luminous center being of a greater power than the ordinary light conditions of the car interior for displaying the characters, a partition wall between the character-bearing surface and the luminous center, said partition having an opening therein of a size to accommodate the characters, condensing lenses interposed between the luminous center and the partition wall and in alinement with the opening therein, a projecting surface, an enlarging lens interposed between the projecting surface and the character-bearing surface, a wall within the casing, serving as a mounting for the enlarging lens and the projecting surface, and means for actuating the character-bearing surface in a step by step movement, substantially as described.

10. In an indicating device, the combination of a casing, a character-bearing surface within the casing, composed entirely of flexible material and having characters formed thereon, the characters and bearing surface therefor being of different degrees of transparency, a luminous center, within the casing, said luminous center being of greater power than the ordinary light conditions of the car interior for displaying the characters, a partition wall between the character-bearing surface and the luminous center, said partition having an opening

- therein of a size to accommodate the characters, condensing lenses interposed between the luminous center and the partition wall and in alinement with the opening therein, 5 a projecting surface, an enlarging lens interposed between the projecting surface and the character-bearing surface, means for actuating the character-bearing surface in a step by step movement, and means for reversing the direction of movement of the character-bearing surface, substantially as described.
11. In a station indicating device, the combination of a flexible strip having at recurring intervals, surfaces forming characters, indicating stations, the character-bearing surfaces and characters being of different degrees of transparency, a projecting surface, a luminous center, the 15 density of light emanating from said center being stronger than the normal light in the interior of the car, whereby the light projected through the strip and onto the projecting surface will be of greater density than the light in the interior of the car body, and means for moving the strip, substantially as described.
12. In combination with a car body having a roof projecting above the roof of the 20 car vestibule, an indicating device located above the vestibule roof and adjacent the end of the car roof, said indicating device consisting of a flexible strip having at recurring intervals surfaces forming characters 25 indicating stations, the character bearing surfaces and characters being of different degrees of transparency, a projecting surface occupying an open space immediately 30 below the roof of the car body at the end thereof, a luminous center located on the reverse side of the projecting surface and

immediately above the vestibule roof, the luminous center being such that the density of light emanating therefrom will be stronger than the normal light from the interior of the car whereby the light projecting through the strip onto the projecting surface will be of greater density than the light in the interior of the car body, and means for moving the strip, substantially as 45 described.

13. In combination with a car body having a partition wall dividing the car body into a passenger portion and a vestibule portion, said wall having near the roof of the car an open space, a projecting surface occupying said open space and visible from the interior of the passenger portion of the car, an indicating device located at the top of the vestibule portion of the car and adjacent to and exterior of the projecting surface, said indicating device consisting of a flexible strip having at recurring intervals surfaces forming characters indicating stations, the character bearing surfaces and characters being of different degrees of transparency, and a luminous center located adjacent to and on the reverse side of the flexible strip, said luminous center being such that the density of light emanating therefrom will be stronger than the normal light from the interior of the car, whereby the light projecting through the strip onto the projecting surface will be of greater 60 density than the light in the interior of the car body, and means for moving the strip, substantially as described.
